No. 865,618.

PATENTED SEPT. 10, 1901

C. P. STEINMETZ.
PRODUCTION OF NITROUS COMPOUNDS.
APPLICATION FILED APR. 20, 1907.Fig. 2.

UNITED STATES PATENT OFFICE

CHARLES P. STEINMETZ, OF SCHENECTADY, NEW YORK, ASSIGNOR TO GENERAL
COMPANY, A CORPORATION OF NEW YORK.

PRODUCTION OF NITROUS COMPOUNDS.

No. 865,618.

Specification of Letters Patent.

Patented Sept.

Application filed April 20, 1907. Serial No. 369,263.

To all whom it may concern:

Be it known that I, CHARLES P. STEINMETZ, a citizen of the United States, residing at Schenectady, county of Schenectady, State of New York, have invented certain new and useful Improvements in Production of Nitrous Compounds, of which the following is a specification.

My invention has reference to a process of and apparatus for manufacturing nitrous compounds from atmospheric air by exposing the air to the action of an electric arc of minimum volume and greatest practicable length.

Heretofore it has been deemed necessary for the practical and efficient production of nitrous compounds from atmospheric air to employ a large number of arcs simultaneously which were established without actual initial contact. These arcs, therefore, when first established, were of short length and were then drawn out to their maximum length until they broke. This establishing, lengthening and breaking of the arcs was repeated in rapid recurrent successions, while the air from which the compounds were to be produced was drawn to and past the arcs in a continuous stream, which carried off the nitrous compounds that had been produced, so that they were not acted upon again to any appreciable extent by the arcs. This old process, requiring as it does the use of a great number of electric arcs and of high tension currents, is expensive and troublesome, and the apparatus employed is liable to get out of order, and, owing to the multiplicity of the arcs employed, the readjustments or repairs are exceedingly troublesome and time-consuming, since ordinarily, the whole apparatus has to be taken to pieces for this purpose. By my invention, these difficulties are overcome by the employment of a single electric arc maintained by direct current, and which arc is deflected or drawn out laterally, magnetically, to a distance within which it can be safely maintained, and it is also magnetically rotated within its sphere of action, so that it sweeps through the air which is to be converted into nitrous compounds.

In the accompanying drawing, which forms a part of this specification, the apparatus adapted for the practice of the process is illustrated as follows:—

45 Figure 1 represents an elevation of the apparatus as a whole, showing the converting chamber and its appurtenances in vertical section; Fig. 2 is a horizontal section of the converting chamber and its appurtenances; and Fig. 3 is a diagram of another form of apparatus that may be employed.

Like numerals of reference indicate like parts throughout the drawing.

Referring to Figs. 1 and 2, the cylindrical air chamber 1 of insulating material, such as glass or porcelain,

is provided with a removable cover 2 and 3 by which the chamber is supported and held by radial arms 5, the outer ends of which are secured to an annulus 6 which is supported by arms 7. Any other mode of supporting the chamber may be used.

In the bottom of the chamber there is a surmounted by a short, inwardly projecting rim, there may be a number of such openings at the admission of air, which is drawn into the chamber through these openings by a suitable pump, being provided with a tube 10' which passes through the chamber. The suction pump and the apparatus for disposing of the mixture of air and nitrogen which is drawn from the chamber form a part of the invention, and the pump is therefore automatically indicated.

In the center of the bottom of the air formed a suitable opening for the insertion of electrode 11, and a similar opening is provided in the cover 2 for the insertion of the electrode 10, and the usual means are provided for holding the electrodes in position. These electrodes are made of any suitable material for establishing a discharge arc between them, such as tungsten, but other materials are available.

Below the chamber 1 is mounted a frame 2 having suitable bearings for a vertical shaft 14 which carries a pulley 15 driven by a belt 16 from an electric motor 18. Any other means for driving the shaft 14 by the electric motor may be used. To the upper free end of the shaft 14 is secured a cage or cage formed with four upwardly and outwardly curved arms 19, upon the free ends of which is mounted the ring yoke 20 of the electromagnet, the legs of which project inwardly toward the center of the cage so that the magnetic flux passes substantially at right angles to the axis of the arc. The extended electromagnet 20 largely surround the air chamber, substantially in the manner in which the field poles of an electric motor surround the armature.

The circuit connections in this apparatus are as follows:—The current, from any suitable source of current, enters the motor by the conductor 23 and brush 24, and passes by conductor 25 and brush 26, to the winding of one leg of the electromagnet, and by conductor 27 to the winding of the other leg of the electromagnet; then by conductor 28 to the collector ring 29, and by brush 30 and conductor 31 to the electrode 12, through the arc to the anode 11, and by conductor 32 back to the generator. It will be noticed that part of the conductor 32 passes over the outer face of the air chamber which, for example, may have a longitudinal groove formed

in Fig. 2, at 33. The conductor 32 is lodged in groove, so that it will not project beyond the outer of the air chamber.

It will be seen that by the construction described, the motor (not shown), the motor, the electromagnets and electrodes between which the arc is established are in series. The consequence of this arrangement is that the resistance of the arc largely controls the speed of the motor. The rotating electromagnets have the function of deflecting the arc as shown in the diagram, and of rotating the arc about the common axis of the two electrodes, so that this arc sweeps through the greater part of the space of the air chamber and acts upon the air to produce a chemical combination between the nitrogen and oxygen to produce mostly gaseous compounds, which are drawn off by the vent. If any small quantities of liquid nitrogen should form, which may sometimes happen, the same will accumulate at the bottom of the air chamber and may be drawn off, at long intervals, in any desired manner. The inwardly projecting short tube 9 at the bottom of the air chamber is provided to prevent the untimely discharge of liquid nitrogen which, coming in contact with the metallic parts of the apparatus, might injure the same.

In starting the apparatus, the upper electrode is actuated with the lower one. When the current is caused to pass, the upper electrode 11 is slowly drawn down to establish the arc of such length as is suited to the strength of the current employed, and the windings and iron of the magnets are so proportioned that the minimum practicable deflection of the arc is obtained. It has been found that when an arc is laterally deflected by a magnet, it displays a tendency to creep between the electrodes, above and below, respectively, the points between which the arc is primarily established. This results in disfigurement of the electrodes by the end of the arc. In order to prevent such disfigurement the electromagnets are formed with subsidiary pole pieces 34, two for each main pole piece, and are arranged on opposite sides of the vertical diameter of the magnet cores, and outside of the winding of the main pole pieces. These subsidiary pole pieces (which are, of course, magnetically connected with the yoke 20), have the opposite polarity from that of the main pole pieces, so that they act to repel the arc at the points between the electrodes when the main pole piece acts to draw the central portion of the arc, and vice versa. In this manner the arc, while being powerfully drawn out in one direction, has no tendency to creep up and down, respectively, on the body of the arc. This refinement of construction is not absolutely necessary, since it is quite practicable to do without it.

The rotation of the deflected arc serves the double purpose of extending the sphere of action of the arc and of the time within which the arc acts upon any air which passes through the converting chamber.

If the arc were allowed to act upon the air for a longer time than is required to produce the chemical combination of nitrogen and oxygen, it would cause a dissociation of the combination to a considerable extent undo the work which has been done. This is the reason why, in the

former practices, the numerous arcs employed were each maintained for a short period only, so as to allow the removal of the nitrous compounds from the sphere of action of the arcs during the intervals between the successive arcs. The same result is secured by the rotation of the deflected arc in accordance with my invention, since thereby, the arc is continuously removed from the body of the air upon which it has once acted, and this with a practically uniform speed which is determined by the normal speed of the motor.

If for any reason the motor speed should increase, its increased counter-electromotive force would weaken the deflecting magnet and reduce the deflection of the arc, so that its peripheral speed would remain practically the same as before. If, on the other hand, the speed of the motor should, for any reason, momentarily drop, the reduced counter-electromotive force would strengthen the magnet and increase the deflection of the arc, so that its peripheral speed would again remain practically the same as before.

Instead of causing the deflection and rotation of the arc by a rotary magnetic flux produced by mechanically rotated magnets, the same effect may be produced by a rotary magnetic field produced by multiphase currents, in the ordinary well known manner. This is diagrammatically indicated in Fig. 3, where 35 represents a rotary field winding energized by three-phase currents derived from the lines 36 in the usual manner. If this winding is substituted in the construction indicated in Fig. 1 for the rotating magnets there shown, the same result will be produced as with the employment of mechanically rotated magnets. In this case, a separate source 37 of direct current must be employed for feeding the arc between the electrodes 11 and 12, so that while this modification of apparatus is simpler than the one represented in Figs. 1 and 2, it requires two sources of current, one multiphase and the other direct, and for this reason the slightly more complex structure is the preferable one.

It will be understood that instead of using atmospheric air for the production of the nitrous compounds, any other gas mixture containing nitrogen and oxygen in suitable quantities may be employed.

What I claim as new and desire to secure by Letters Patent of the United States, is,—

1. The process of producing nitrous compounds, which consists in rotating a deflected electric arc within a current of air.

2. The process of producing nitrous compounds, which consists in causing a current of atmospheric air and rotating within the same a deflected electric arc.

3. The process of producing the chemical combination of nitrogen and oxygen, which consists in establishing an electric arc of minimum volume and maximum length, deflecting and rotating the arc magnetically, and causing a current of atmospheric air to pass through the space of rotation of the arc.

4. The process of producing the chemical combination of nitrogen and oxygen, which consists in establishing an electric arc, causing a rotating magnetic flux to pass substantially at right angles to the axis of the arc, and passing a current of atmospheric air through or past the arc.

5. An apparatus for the manufacture of nitrous compounds, consisting of means for producing a current of air, and means for rotating and deflecting an electric arc within the air current.

6. An apparatus for producing the chemical combination of nitrogen and oxygen, composed of means for establishing an electric arc of minimum volume and maximum length, means for deflecting and rotating the arc magnetically, and means for causing a current of atmospheric air to pass through the space of rotation of the arc.
- 5 7. An apparatus for producing the chemical combination of nitrogen and oxygen, composed of means for establishing an electric arc, means for passing a rotating

magnetic flux substantially at right angles to the axis of the arc, and means for passing a current of atmospheric air through and past the arc.

In witness whereof, I have hereunto set my hand this 19th day of April, 1907.

CHARLES P. STEINMETZ
